UNITED STATES PATENT OFFICE

117,858

DESIGN FOR A SHIRRED EGG DISH

Joseph Palin Thorley, East Liverpool, Ohio, assignor to The Hall China Company, East Liverpool, Ohio, a corporation of Ohio

Application March 7, 1939, Serial No. 83,408

Term of patent 7 years

To all whom it may concern:

Be it known that I, Joseph Palin Thorley, a citizen of the United States of America, residing at East Liverpool, in the county of Columbiana and State of Ohio, have invented a new, original, and ornamental Design for a Shirred Egg Dish, of which the following is a specification, reference being had to the accompanying drawing, forming a part thereof.

I claim:

The ornamental design for a shirred egg dish, as shown.

JOSEPH PALIN THORLEY.
